UNITED STATES PATENT OFFICE.

LOVELL NEWTON REDDIE OF LONDON, AND BRENCHLEY ERNEST GEORGE MITTELL, OF IVER, ENGLAND, ASSIGNEES TO VICTOR TALKING MACHINE COMPANY, OF CAMDEN, NEW JERSEY, A CORPORATION OF NEW JERSEY.

TALKING-MACHINE RECORD.

Application filed November 18, 1925, Serial No. 69,847, and in Great Britain December 24, 1924.

This invention relates to improvements in and relating to talking machine records.

It is known that a record upon a wax cylinder gives in some respects a more faithful reproduction of the recorded sounds than a record cut upon a disc, and the proposal has been made to record sounds upon a wax cylinder, by the usual or any known method, and to transfer the record so obtained from 10 the cylinder to a disc. It has been proposed to effect this transfer operation by mechanical means such as a lever, one end of which traces in the sound line cut on the wax cylinder whilst the other end of the lever is furnished with a cutting tool whereby a record is cut in a wax disc. From the wax disc a matrix is made in the usual or any suitable way and from the matrix a number of records can be pressed.

20 In this transferring operation it has been proposed not only to transfer an up and down cut from a cylinder and to obtain an up and down cut on a disc, but it has been proposed also to convert the up and down 25 cut on the cylinder into a lateral cut of uniform depth on the disc.

There are certain difficulties in performing this mechanical transferring operation. It is desirable that the tracing point and the recording tool should both rest quite lightly on the surfaces with which they respectively co-operate and it is difficult to arrange a cylinder and a disc sufficiently close to one another to enable the transferring mechanism to be sufficiently light and at the same 30 time sufficiently rigid. The movements of the tracing point and cutting point are necessarily very rapid, where sounds of high frequency are being transferred, and this is 35 true even though in the transferring operation the cylinder and disc are rotated at much lower speeds than those at which the cylinder was first recorded and the disc record will be played. If the transferring 40 mechanism possesses any considerable mass, it will be understood that these rapid movements result in the tracing point and recording tool respectively performing movements which do not accurately correspond to the 45 sound record cut on the wax cylinder. If in the transferring operation an up and down cut on the cylinder has to be converted into a lateral cut on the disc the difficulties as referred to above are increased.

One of the objects of the present invention is to remove these difficulties in the operation of transferring from one recorded surface to another.

According to the present invention, in the transformation of a sound record of one kind into a sound record of a different kind, the sound after being recorded is converted into electrical oscillations which are adapted to operate a recording device.

Further, according to the present invention a sound record of any kind may be transferred to a sound record cut in a solid body, that is to say, a record adapted to be reproduced by mechanical means, by converting the first sound record into electrical 70 oscillations which are caused to cut the record in the solid body.

Means may also be provided for modifying the electrical oscillations either to accentuate or to diminish certain ranges of 75 frequency or to alter the amplitude of the whole, and to permit of the adjustment of these controlling means a reproducer or loud speaker may be connected in such a manner as to reproduce the electrical oscillations in 80 the form in which they are being recorded.

One method of carrying out the invention will now be described, by way of example, with reference to the accompanying drawing in which is shown diagrammatically a 85 method of transferring a sound record, of either up and down or lateral cut type, from a cylinder to form a record, of either up and down or lateral cut type, upon a disc.

A reproducing stylus *a* traces lightly in 90 and is oscillated by the sound line upon the rotating cylinder *b* and thereby generates feeble oscillating currents in the primary *c* of the input transformer *d*. The reproducing device *e* may be of any known or 95 suitable form. The oscillating electro-motive forces set up in the secondary *f* of the transformer *d* are impressed upon the grid circuit of a thermionic valve *g* which is the first valve of an amplifier which may 100 comprise any desired number of valves although, in the present example, three are shown. The intervalve coupling illustrated is of the well known resistance-capacity type. The oscillating currents from the last 105 amplifying valve *b* are passed through the primary *i* of an output transformer *j* and currents generated in the secondary *k* of this

transformer pass to the recording device *l*, which may be constructed along the same lines as the reproducing device *e*. The stylus *m* of the recording device *l* cuts a record upon the rotating disc *n*.

Control of the volume and quality of the sound transmitted is obtained by the following means: The primary *c* and the secondary *f* of the input transformer *d* are 10 made so that their inductances are variable either by means of suitable tappings or otherwise and a variable condenser *o* is connected in parallel with the secondary *k* of the output transformer *j*. Adjustment of 15 each of these three controlling means will alter both the amplitude and the wave form of the electrical oscillations but in the main it may be said that adjustment of the primary *c* and of the condenser *o* serves to control 20 the wave form of the oscillations whilst adjustment of the secondary *f* mainly affects the amplitude of the oscillations since the currents flowing in the grid circuit are only those due to inter-electrode capacity and are 25 consequently very small compared with the currents flowing in the circuits of the reproducing device *e* and of the recording device *l*. In order that the operator may be able 30 to listen to the sounds in the form in which they are being recorded and so make any necessary adjustments during the process of transference, a loud speaker *p* is provided and is connected across a small portion of a resistance *q* which is shunted across the 35 secondary *k* of the output transformer *j*, the currents required to operate the recording device *l* being in general much greater than those required to operate the loud speaker satisfactorily.

40 The record upon the cylinder may be made by the direct action of sound waves upon a diaphragm connected with the recording tool or the sound waves may be allowed to strike a microphone, or equivalent means for converting 45 sound oscillations into electrical oscillations, and to produce electrical oscillations in a circuit containing a suitable thermionic amplifier, the amplified oscillations being used to operate an electrical recording device, or the record on the cylinder 50 may be produced in any other known or suitable manner.

The tracing point and also the recording tool used in the transferring process may be 55 made very light and the transferring may take place at a speed considerably lower than that at which the record was originally made so that the movement of the oscillating parts can be made to correspond very accurately with the sound record cut on the cylinder. In order to still further reduce the 60 possibilities of distortion due to the inertia of moving parts a record may first be made by any known process, such as that employing a cathode ray oscilloscope device, in

which all oscillating parts are substantially inertia-free and this record may then be transferred by the method according to the present invention, at a reduced speed, to a record which is in the most convenient form 70 for reproduction. In the case of the production of a wax record, the speed may be adjusted so that substantially no distortion is introduced owing to the mass of the oscillating stylus and the most suitable cutting 75 speed for the wax may also be taken into consideration.

The present invention, therefore, is not confined to the operating of transferring a sound record from a wax cylinder to a disc. 80 Sound records are well known in the form of films, for example, on which a photographic record is made, a beam of light which falls on the film being moved, or its intensity being varied, by and in accordance with 85 sound waves, or the photographic sound record may be produced by a cathode ray oscilloscope device. From these photographic records, sound has been reproduced in a variety of ways, as for example by passing 90 light through them, whilst in motion, on to a light-sensitive cell, from which a variable current is derived, and this current, after amplification by means of thermionic valves for example, is used to actuate a loud 95 speaking telephone; or the photographic film may be used to provide a variable capacity, to vary an electric current in accordance with the sound waves recorded.

Sound records are also known which are 100 recorded by effecting the variable magnetization of metal bodies such as wire, metal ribbons, or metal discs, and from these records variable electric currents are derived by suitable means which, after amplification by 105 thermionic valves, actuate a loud speaking telephone.

Sound records in the form of films, ribbons or wire are not easily handled, and the apparatus for reproducing therefrom is of 110 a delicate and highly technical nature and not of a kind suitable for use by the general public.

The present invention may be applied to the purpose of obtaining, from sound records 115 of the above mentioned type, or from whatever type of record constitutes an accurate and faithful record of the sounds which it is desired to reproduce, electrical currents or current impulses which after amplification 120 by thermionic valves, are used to operate a recording tool to cut a record in a body of a convenient form for handling, such as a cylinder or disc, which (or duplicates of which) can be reproduced with a talking machine, that is to say, can be reproduced 125 by mechanical means.

A further application of the present invention is in the preparation of a new wax blank from an existing talking machine ma- 130

trix or record. There are matrices which have been in existence for several years and possess considerable historical and musical value, but may have some imperfections due 5 possibly to the less perfect recording method in use when they were made. A suitably formed tracing point can be made to track on these matrices, or on a record made therefrom, the currents thereby produced are amplified as above described and a new wax blank is cut. During the transferring process the amplification of any imperfect passages can be modified, as for example by reducing the amplification of a passage that 10 is too loud, by increasing momentarily the resistance in some part of the circuit, or the quality of certain passages can be altered (e. g. to bring out the overtones) by using a variable condenser in series in the circuit 15 to or from the amplifier, the overtones being emphasized by reducing the capacity.

We claim:

1. The method of transforming a mechanically recorded sound record into an electro- 20 mechanically recorded sound record which consists in employing the sound record to be transformed for producing mechanical vibrations, converting said vibrations into feeble oscillating currents in an electrical circuit, audibly reproducing said currents, vari- 25 ably controlling both the amplitude and the wave form of said currents according to the audible reproduction to render the same more pleasing, transferring the currents so controlled into mechanical vibrations, and recording said mechanical vibrations on the other record.

2. The method of transferring sound mechanically recorded on by a sound record onto a recording surface which consists in 40 moving said sound record at a speed considerably lower than that at which said sound record was originally made, employing said slowly moving record for producing feeble oscillating currents in an electric circuit, 45 audibly reproducing said currents, variably controlling both the amplitude and wave form of said currents according to the audible reproduction to render the same more pleasing, and transferring the currents so 50 controlled onto said recording surface.

3. The method of transferring a sound record from a cylinder onto a disk which consists in moving said cylinder at a speed considerably lower than that at which said 55 sound record was originally made, employing the sound record to be transferred for producing mechanical vibrations, converting said vibrations into feeble oscillating currents in an electrical circuit, audibly repro- 60 ducing said currents variably controlling both the amplitude and wave form of said currents according to the audible reproduction to render the same more pleasing, trans- 65 ferring the currents so controlled into mechanical vibrations and recording said mechanical vibrations on said disk.

In testimony whereof, we have signed our names to this specification at London, England, this third and fourth days of November, 70 1925, respectively.
